US0D1035437S

(12) **United States Design Patent** (10) **Patent No.:** **US D1,035,437 S**
(45) **Date of Patent:** **** Jul. 16, 2024**

(54) **ABSORBENT ARTICLE PACKAGE**

- (71) Applicant: **The Procter & Gamble Company**, Cincinnati, OH (US)
- (72) Inventors: **Lee Anne Hilsabeck**, Cincinnati, OH (US); **Holly J. Shoemaker**, Cincinnati, OH (US)
- (73) Assignee: **The Procter & Gamble Company**, Cincinnati, OH (US)
- (**) Term: **15 Years**
- (21) Appl. No.: **29/761,077**
- (22) Filed: **Dec. 7, 2020**

(57) **CLAIM**

The ornamental design for an absorbent article package, as shown and described.

DESCRIPTION

FIG. 1 is a front, right and top perspective view of the first embodiment of an absorbent article package showing our new design;

FIG. 2 is a view of the front side of the package of FIG. 1; FIG. 3 is a view of the right side of the package of FIG. 1; FIG. 4 is a view of the back side of the package of FIG. 1; FIG. 5 is a view of the left side of the package of FIG. 1; FIG. 6 is a view of the top side of the package of FIG. 1; and FIG. 7 is a view of the bottom side of the package of FIG. 1.

FIG. 8 is a front, right and top perspective view of the second embodiment of an absorbent article package showing our new design;

FIG. 9 is a view of the front side of the package of FIG. 8; FIG. 10 is a view of the right side of the package of FIG. 8; FIG. 11 is a view of the back side of the package of FIG. 8; FIG. 12 is a view of the left side of the package of FIG. 8; FIG. 13 is a view of the top side of the package of FIG. 8; and, FIG. 14 is a view of the bottom side of the package of FIG. 8.

The broken lines are shown for the purpose of illustrating parts of the article which form no part of the claimed design.

1 Claim, 4 Drawing Sheets
